Primary Examiner — Rosemary K Tarcza*Assistant Examiner* — Christy Nemeth(74) *Attorney, Agent, or Firm* — Mintz Levin Cohn Ferris Glovsky and Popeo, P.C.; Kongsik Kim(57) **CLAIM**

The ornamental design for an inverter, as shown and described.

DESCRIPTION

FIG. 1 is a perspective view of an inverter according to the present invention.

FIG. 2 is a front view of the inverter of FIG. 1.

FIG. 3 is a rear view of the inverter of FIG. 1.

FIG. 4 is a left side view of the inverter of FIG. 1.

FIG. 5 is a right side view of the inverter of FIG. 1.

FIG. 6 is a top view of the inverter of FIG. 1; and,

FIG. 7 is a bottom view of the inverter of FIG. 1.

The broken lines in the drawings illustrate elements of the inverter that form no part of the claimed design.

1 Claim, 7 Drawing Sheets(56)
